ASSIGNORS TO STACKHOUSE & ALLEN, OF CHICAGO, ILLINOIS, A PARTNERSHIP
CONSISTING OF JOHN H. STACKHOUSE AND JOHN R. ALLEN.

ELECTRICAL SCREW PLUG.

Application filed March 6, 1922. Serial No. 541,477.

Our invention relates to electrical screw plugs and more particularly to a plug that can be assembled with a minimum number of operations.

5 It is a purpose of the invention to provide an electrical plug with which the ends of conductors are adapted to be connected by a minimum number of assembling operations, and which in its preferred form can 10 be assembled without the use of tools or solder.

It is a further purpose of the invention in one of its forms to provide an electrical screw plug having a body portion of insulating material upon which a screw shell is adapted to be mounted, said screw shell being provided with means for locking the same to said body portion, said body portion being provided with a central contact member and a cap which is adapted to be mounted on said body portion by engagement with the central contact of the body portion, said cap member being so constructed that the same will lock itself against turning relative to the body portion after the parts are in assembled relation.

It is another purpose of the invention to provide an electrical screw plug of the form described above with a central contact member embedded in the body portion of the plug, said central contact member being provided with a screw threaded end portion with which a central contact member on said cap is adapted to screw threadedly engage, said cap being provided with means for locking the same against rotation after being moved to proper assembled relation with respect to the body portion.

It is still a further purpose of the invention in one of the forms shown to provide a plug having a body portion from one end of which a central screw threaded contact member projects, said contact member being adapted to receive the end portion of a conductor therearound, and said body portion being provided with a screw shell which is adapted to clamp the end of the other conductor of a pair between said screw shell and body portion and to provide a cap member with a screw threaded member adapted to engage with said screw threaded projecting portion on said body portion to clamp the end of one of the conductors be-

tween the same and said projecting central contact, said cap also serving to lock the parts in assembled relation. The invention can be applied to plugs of various types, two different forms being shown in the drawing. In one of these forms the screw shell is provided with similar means for locking the same to the body portion and for locking the cap thereto. However, in the preferred form of the invention it is a particular purpose of the invention to provide locking means between the cap member and the screw shell which comprises prongs on the screw shell and ratchet teeth on the cap. A similar locking means can also be used between the screw shell and the body portion when this is desirable.

Other objects and advantages of the invention will appear as the description of the accompanying drawings proceeds. However, we desire to have it distinctly understood that we do not intend to limit ourselves to the exact details shown or described, but that we intend to include as part of our invention all such obvious changes and modifications of parts as would occur to a person skilled in this art and as would fall within the scope of the claims.

In the drawings:

Fig. 1 is a longitudinal sectional view of our improved screw plug showing the parts in assembled relation and showing the form of plug wherein the same form of locking means is used for locking the screw shell against turning relative to the body portion as is used for locking the cap to the screw shell;

Fig. 2 is a sectional view taken on the line 2—2 of Fig. 1 looking in the direction of the arrows;

Fig. 3 is a section taken on the line 3—3 of Fig. 1 looking in the direction of the arrows;

Fig. 4 is a section taken on the line 4—4 of Fig. 1 looking in the direction of the arrows;

Fig. 5 is a side elevational view of a plug such as that shown in Fig. 1, said plug being shown as being partly broken away and being shown as substantially of actual size;

Fig. 6 is a view similar to Fig. 1 of a plug which is assembled in a similar manner, and which is provided with similar means for locking the central contact carrying cap

member to the screw shell, the form of plug shown being what is commonly known as a divided or two part plug;

Fig. 7 is a section taken on the line 7—7 of Fig. 6;

Fig. 8 is a section taken on the line 8—8 of Fig. 6; and

Fig. 9 is an enlarged fragmentary sectional view showing the locking connection between the cap member and the screw shell.

Referring in detail to the drawings, the improved plug comprises a body portion 10 which is provided with the usual enlarged end portion 11 and which has a central opening 12 for receiving the usual pair of conductors. The opening or passage 12 connects with a substantially longitudinally extending passageway 13 extending through to the inner or opposite end of the body portion and with a substantially laterally extending passage 14 which extends through the side portion of the body member 10 in alignment with the screw threaded portion 15 thereof. The screw threaded portion 15 of the body portion 10 is adapted to receive the similarly threaded portion 16 of the screw shell 17. It will be noted that at the junction of the passages 12, 13 and 14 a rounded shoulder 18 is provided which aids in guiding the ends of the conductors passed inwardly through the opening 12 into the passages 13 and 14. Embedded in the body portion of the member 10 at the inner end thereof is the central contact member 19 which is provided with the flanges 21 to hold the same rigidly in position in the member 10, and which is provided with an outwardly extending screw threaded portion 22 around which the end portion of a conductor is adapted to be placed.

The screw shell 17 is provided with an in-turned flange portion 23 at one end thereof, the flange portion 23 being adapted to seat against the end portion of the body member 10. The flange 23 is provided with a plurality of tongues or projections 24 that are struck inwardly toward the screw threaded portion thereof, and similar tongues or projections that are struck outwardly away from the main portion of the screw shell. The material of the screw shell is of sufficient resiliency that the tongues 24 and 25 will have a spring action. The tongues 24 and 25 are formed by providing the transversely extending slots 26 on the flange 23 and the circumferential slots 27 therein. The end portion of the body member 10 is provided with a plurality of teeth or projections thereon which have inclined portions 28 and substantially flat portions 29.

It will be noted when looking down on the member 23 as shown in Fig. 4 that as the screw shell 17 is tightened on the member 10 by a clockwise turning movement thereof, the flexible tongue 24 will ride over the in-

clined portions 28 of the teeth but that when a reverse movement of the screw shell 17 is attempted at least one of the tongues 24 will engage with one of the abrupt shoulders 30 to prevent the unscrewing of the shell from the plug. The plug also comprises a cap member 31 which is provided with a central contact member 32 having a reduced portion 33 provided thereon so that the said member 32 can be molded in the member 31 and firmly held in position therein. The member 32 is also provided with a screw threaded portion 34 adapted to screw threadedly receive the screw threaded portion 22 of the member 19, thus establishing electrical connection between the members 19 and 32 and the end of the conductor clamped between said members. The cap member 31 is also provided with a plurality of teeth or projections thereon comprising the inclined portions 35 and the flat portions 36, said inclined portions 35 being inclined at such an angle that as the member 31 is turned in a direction to tighten the same on the body member 10 by engagement between the screw threaded portions 22 and 34, the tongues 25 will ride over the inclined surfaces 35, but that if a movement of the member 31 in a direction to remove the same from the body member 10 is attempted, the end portion of one of said tongues 25 will engage with a shoulder or abutment 37 provided between each of the inclined portions 35 and a flat portion 36. Thus the cap 31 will be locked against removal from the body portion 10 and will hold the parts of the device in assembled relation.

It will be noted that the main body portion 10 is provided with an annular projection or shoulder 38 which is adapted to enter a recess 39 in the cap member 31, a ledge 40 being provided adjacent the flange or shoulder 38. The flange or projection 38 is provided to form a partition between the screw shell and the central contact member, so that no loose strands of the wire connected with the central contact will be liable to come into engagement with the screw shell and cause a short circuit.

The device is assembled as follows:

The members 10, 31 and 17 are shipped in disassembled condition and in connecting the plug on the end of a conductor comprising a pair of conducting members, the bare end of one of said conducting members is passed through the passage 14 and positioned against the outer side wall portion of the member 10 provided with the screw threads 15, then the screw shell 17 is threaded on the said portion clamping said bare end between the screw shell and body portion. The screw shell is turned on to such an extent that at least one of the tongues 24 will enter one of the recesses to a sufficient extent so that the same will engage with a shoulder 30 to prevent turning of the member 17 in a

reverse direction. The other conducting member is passed through the passage 13 so as to project beyond the same at the same time that the first mentioned conductor is 5 passed through the passage 14, thus separating the conductors so that one of the same enters one of the passages and the other enters the other passage, this being accomplished by the rounded projection 18 10 at the junction of the passages. The bare end of this conductor is then wrapped around the screw portion 22 after which the cap 31 is threaded onto the same by engagement of the threads on the member 32 with 15 the threads on the member 22. The member 31 is screwed onto the member 10 to such an extent that at least one of the tongues 25 enters one of the recesses in the cap member to a sufficient extent so that the same 20 will engage with one of the shoulders 37 so as to prevent return rotation of the cap member, thus locking the cap member in position on the body portion.

It will thus be noted that the flange member 23 with its tongues 24 and 25 acts as a locking washer both for the screw shell and for the cap member 31, and that when the parts are assembled as described above that a plug will be provided which is a non-separable plug, and which is one that can be readily assembled without the use of tools, and due to the fact that the assembling thereof is a hand operation entirely, said assembling can be very quickly accomplished. The 35 form of screw plug shown in Figs. 6 to 9 inclusive embodies the same principles as the plugs shown in Figs. 1 to 5 inclusive, but is of a different type, being a two-part or separable plug. Said separable plugs comprise 40 a member 41 having the bare ends of the pair of conductors associated therewith electrically connected with the prongs or projecting contact members 42 which are adapted to enter the sockets or recesses 43 in the member 44, contact members 45 and 45' being provided in said recesses 44 for establishing electrical connection with the members 42. The members 45 and 45' are made of material 45 of sufficient resiliency so that the same 50 will grip the members 42 with a spring action. The member 44 is provided with a screw shell 46 which surrounds the substantially cylindrical portion 47 of the member 44 and which is provided with screw threads 48 adapted to screw on the threads 48' provided on the member 44 to hold said screw shell on the body portion 44. The member 46 is provided with a flange portion 49, which is substantially annular, and is provided 55 with radially extending slots 50 and circumferentially extending slots 51, whereby prongs or projections 52 are provided which are struck outwardly from said flange so as to provide resilient fingers for securing the cap 53 in position on the member 44,

The cap 53 is provided with inclined faces 54 and with flat surfaces 55 providing shoulders 56 between said inclined portions 54 and straight portions 55 against which the ends of the fingers are adapted to abut to 70 prevent turning of the member 53 in such a direction that the same can be disengaged from the member 44, said member 53 having screw threaded engagement with the member 44. The member 44 is provided with a 75 screw 57 having enlargements 57' imbedded in the member 44 which is adapted to enter the screw threaded bore 58 in the central contact member 59 of the cap 53, said contact 80 59 being provided with a reduced portion 60 for a purpose previously described and engaging with the collar-like portion 61 which is made integral with the finger 45, said portion 61 being indented as at 62 so as to engage snugly with the screw 57. 85

From the above it will be seen that a connection is provided between one of the spring contacts 45 and the central contact member 59 and between the other spring contact 45' and the screw shell 46. It will also 90 be seen that the member 53 acts as a locking member to hold the parts in assembled relation, and furthermore that a device of this character can be quite easily assembled compared with the common form of separable or 95 two-part screw plugs. It will be noted that the member 53 in this case is provided with an annular projection or boss 63 which serves to separate the central contact from the screw shell so as to prevent accidental short 100 circuiting between the same.

Having thus described our invention, what we desire to claim and secure by U. S. Letters Patent is:

1. An electrical plug of the character described comprising a body portion, a screw shell mounted thereon, a cap, means for securing said cap to said body portion and means for locking said cap in position comprising ratchet teeth on said cap for locking the same against turning relative to said body portion and yieldable means between said cap and body portion. 105

2. An electrical plug of the character described comprising a body portion, a screw shell mounted thereon, a cap, means for securing said cap to said body portion and means for locking said cap in position comprising an inclined portion on said cap for locking the same against turning relative to 110 said body portion and yieldable means between said cap and body portion. 120

3. An electrical plug of the character described comprising a body portion, a screw shell mounted thereon, a cap member having a contact thereon, means on said body portion for securing said cap member thereto and means for locking said cap in position on said body portion, said means comprising 125 yieldable means mounted between said cap 130

and body portion cooperating with inclined portions on said cap and body portion.

4. An electrical plug of the character described comprising a body portion having 5 ratchet teeth thereon, a screw shell mounted on said body portion and having means thereon adapted to engage said ratchet teeth to lock said screw shell against rotation in one direction, a cap member having a contact thereon and means on said body portion 10 for securing said cap member thereto, said cap member being provided with ratchet teeth and said screw shell having means co-operating with said ratchet teeth to lock 15 said cap member against rotation relative to said screw shell in one direction.

5. An electrical plug of the character described comprising a body portion having ratchet teeth thereon, a screw shell having 20 prongs thereon projecting towards said body portion and engaging with said ratchet teeth to lock said screw shell against rotation in one direction, a cap member having a contact thereon, said cap member being provided 25 with ratchet teeth, and means on said body portion for securing said cap member thereto, said screw shell being provided with prongs extending toward said cap member to lock said cap member against rotation in 30 one direction.

6. An electrical plug of the character described comprising a body portion, a cap member having a contact thereon, means on said body portion for securing said cap member thereto, said body portion and said cap member being provided with ratchet teeth on the opposed faces thereof, and a screw shell mounted on said body portion and having a flange extending between said body portion

and said cap member, said flange being provided with oppositely directed resilient 40 tongues adapted to engage with said ratchet teeth to lock said screw shell and said cap member against rotation in one direction.

7. An electrical plug of the character described comprising a body portion of insulating material, a conducting screw shell mounted thereon, means for automatically locking said shell in position on said body portion, a cap having a contact thereon mounted upon said body portion, and automatic means for locking said cap in position.

8. An electrical plug of the character described comprising a body portion of insulating material, a conducting screw shell screw-threadedly mounted thereon, means for automatically locking said shell in position on said body portion, a cap having a contact thereon mounted upon said body portion, and automatic means for locking said cap in position.

9. An electrical plug of the character described comprising a body portion of insulating material, a conducting screw shell screw-threadedly mounted thereon, means for automatically locking said shell in position on said body portion, said shell being adapted to clamp a lead-in conductor in place on said body portion, a cap having a contact thereon mounted upon said body portion, and automatic means for locking said cap in position.

In witness whereof, we hereunto subscribe our names this 27th day of February, A. D. 1922.

JOHN H. STACKHOUSE
JOHN R. ALLEN.
